MECHANISM FOR TREATING ORE.

1,027,110.

Specification of Letters Patent. Patented May 21, 1912.

Application filed December 23, 1907, Serial No. 407,860. Renewed February 17, 1910. Serial No. 544,507.

To all whom it may concern:

Be it known that I, ARTHUR S. DWIGHT, a citizen of the United States, residing at New York, in the county of New York and 5 State of New York, have invented certain new and useful Improvements in Mechanism for Treating Ore, of which the following is a specification, reference being had therein to the accompanying drawing.

10 This invention relates to improvements in apparatus for treating ores, it being particularly intended for the desulfurizing and sintering of ores of the sulfid class.

The object of the present invention is to 15 provide a mechanism for this purpose which shall be composed of simply constructed elements which can be readily repaired and which can be employed to greater advantage in several respects than 20 can the machines that have been heretofore used for this work.

Figure 1 is a side elevation of a machine embodying my improvements; Fig. 2 is a side view of one of the pallets or ore receptacles with some of the adjacent parts also 25 shown; Fig. 3 is a cross section showing one of the pallets and part of the air suction box.

In these drawings A represents an air 30 suction box upon the upper edges of which are wearing strips B, carefully planed and upon which slide the cast iron pallets D, the lower edges of which are likewise carefully planed and the vertical edges of 35 which are also planed so as to make airtight joints when the pallets are pushed along the top surface of the box. The pallets carry the grates C which rest upon lugs M cast on the inner sides of the pallets. 40 The pallets are each built with transverse members S—S¹ (Fig. 2) which form, of the lower part of the pallet, a four-sided box, while the upper part above the grate has these transverse members omitted so 45 that the ore charge can be continuous. These lower transverse members serve as partitions to cut off the air at certain points. Each of these pallets may be described as an independent or individual car provided 50 with four wheels E attached to the pallet by suitable lugs and so placed that the centers of the axles shall be in a line with the lower edges of the pallets, thus permitting each pallet to move around the curved track

hereinafter described without interference 55 with the other pallets. As the pallets are being pushed across the suction box, they are guided by the flanges of the wheels E engaging with the inner edges of the longitudinal tracks F though the treads of the 60 wheels do not rest upon said track, the weight of the pallets being sustained by contact at the strips B, as already mentioned. Instead of steering the pallets, by guiding the flanges of the wheels, it may be accomplished also by shaping the lugs carrying 65 the axles of the wheels in such a way that they will fit over the wearing strips along the surfaces B and thus guide the pallets in a straight line while traveling over the 70 suction box.

At each end of the suction box there is arranged an adjustable deadplate G¹, the upper surface of which is flat and coincident with the plane of the surfaces of strips 75 B, and upon this surface the lower edges of the pallets will move with an airtight joint just before they pass in their travel to a position over the suction box and again just after they pass the suction box. These 80 deadplates have a length slightly longer than the length of a pallet, so that there will be no leakage of air during the time that a given pallet is partly over the suction box either entering or leaving. In 85 order to compensate for wear these deadplates should be made adjustable, vertically, by slot bolts or otherwise.

The pallets are elevated, one by one, and consecutively placed in position on the rails 90 F by means of a pair of sprocket wheels H each of which is so designed that the teeth of the sprocket wheels engage the treads of the wheels E in conjunction with the guide rails F¹ which partially encircle the sprockets leaving room between the sprockets and the rails for the wheels to freely pass. The upper rails F are bent or shaped horizontally inward at their extremity near the sprocket wheel, so as to act as guides for 100 the pallets at the highest point of the lift and direct them horizontally in their travel to the deadplate and suction box.

At the far end of the suction box, or the end farthest removed from the sprocket 105 wheels, the horizontal track F is suddenly curved downward with an outer guide rail F² concentrically arranged with it leaving

sufficient space between the two rails so that the wheels of the pallets may freely pass between them and thus compel the pallets to travel in a circular path at this point, over-turning the same to discharge whatever load they may carry at the bottom of the vertical curve. From the bottom of this curve the track F^3 leads on an incline to the bottom of the sprocket wheels above mentioned in such a way that the idle pallets resting on the inclined track will feed themselves naturally down to the point where the sprockets of the wheels will engage with the wheels of the pallets and carry them 15 consecutively to the upper level.

The suction box is provided with an outlet J which is connected with the suction side of a centrifugal fan or other suitable apparatus for inducing the necessary draft.

K is the hopper for feeding the ore to the sintering machine, while L represents the gas pipe for ignition or other means which may be employed for the purpose.

The grates are preferably made sectional and are here shown with three sections to each pallet, but they might also be made with one section to each pallet if it is found convenient to do so. The grates are preferably made with a rib C^1 to give them 30 strength, or it may be found more convenient to cast transverse partitions or ribs in the lower or box-like part of the pallet and form the grates as flat plates resting on the top of these ribs. The grate is here shown 35 as resting on the lugs M and held in place by the short bolts N .

The structure of the machine can be made in any convenient manner. It is here shown with the suction box forming the principal 40 member, with its weight resting upon the beam O , which also carries the bearings of the sprocket wheel and driving pulley and the framework R of the discharge rails. This beam is in turn supported by the posts 45 P and P^1 . The hopper K and the igniting device L may be supported by extensions of this framework or be hung from an independent framework.

The power to drive the sprocket wheel 50 may be transmitted to it in any convenient manner. In the drawings a driving device is shown in the form of a pulley and belt. Instead of these use can be made of suitably speeded gear wheels.

55 The pallets, being delivered one after another upon the upper edge of the suction box are pushed like a train of cars across it, will successively receive their charges of ore from the hopper K . The ore as it passes under the igniter L will be ignited and immediately come under the influence of the air currents entering the suction box, and the sintering action in the ore on any particular pallet will be continued during the time that the pallet is traveling the

length of the suction box. The speed is so regulated that it will finish its travel across the box at the time, approximately, when the sintering has penetrated to the surface of the grate. By this time the pallet will be 70 ready to discharge its load, and it will do so by being gradually pushed off the level track and on to the first part of the vertical curve, which latter carries it to the lower track. In moving around this curve it will 75 turn upside down and discharge its cake of sinter, which action will be assisted by the suddenness of the descent. This, of course, must be regulated by the proper design of the curves and possibly regulating 80 the force of the descent by restraining devices which will be placed along the line of travel. For instance, friction blocks or impeding devices may be so placed as to break the shock of the descent and regulate 85 it to the desirable degree. As soon as the pallet has discharged its cake of sinter it is able to run down the inclined track F^3 and take its place in the train of pallets 90 waiting to be picked up and elevated by 95 the sprocket wheels.

There are a number of important advantages incident to a machine of this type when compared with those of the types which I have previously designed and built 95 solely or jointly with others. The earlier machines having a series of pallets or receptacles connected together in a series either by linking one to the next or by connecting them to chains had incident to them trouble and inconvenience and were liable to wear out rapidly even when the movable parts were subjected to a slow motion. In the present case, it is made possible to quickly remove any pallet and repair it or 100 substitute a new one without interfering in any way with the continuous operation of the machine. All of the parts of the present machine are comparatively small in size and are so designed that they can be easily 105 constructed in an ordinary foundry or machine shop. I have heretofore constructed machines for this purpose in which the principal element was a large rotary drum or cylinder; and have found that machines of 110 that type can be properly made only in machine shops equipped with large tools such as are not available in mine regions. Again, the pallets in the present construction being independent, each of the others, they can be 115 moved in such way as to more thoroughly effect the detachment and separation of the sinter. When this is to be done, the pallet can have an accelerated speed, in relation to the rest of the series. Moreover, if desired 120 the track-way can be so constructed at points immediately preceding the downward curved track that the pallets will be lifted more or less from the lines of the upper 125 horizontal portion, which will result in frac- 130

turing the sinter cake and in loosening it from the grate.

Under some circumstances, I employ a breaking roller W which acts not only to assist in breaking the sinter cake supported by the terminal pallet in the upper horizontal series, but also serves to prevent the displacement of the sinter in the pallets which are still over the air box.

10 I do not in this case claim a conveying apparatus comprising a movable, open, trough-like carrier for transporting loose material, formed of a series of independent, disconnected elements arranged to be brought together end to end, and means for taking the said elements one at a time from the discharge end of the said series and transporting them to the feed end thereof; nor the combination of such a conveying 15 apparatus with means for feeding material thereto and means for causing a discharge or emptying of the individual conveying elements, as such subjects-matter are claimed 20 in my co-pending case designated as application No. 558,621, filed April 30, 1910.

What I claim is:

1. In an apparatus for treating ore, a series of ore receptacles, movable successively through the region where the ore is treated, means for returning them independently of each other to their initial point of travel and means for delivering an ore-treating gaseous fluid to the ore while supported by the said receptacles, substantially 35 as set forth.

2. In a mechanism for treating ore, the combination with a series of independent pallets or ore receptacles, of means for advancing them through the region where the ore is treated, means for delivering a gaseous fluid to the ore while being advanced 40 through the said ore-treating region, a guide-way along which the said pallets or receptacles return toward the point where 45 they initially commence to travel, and power devices for causing the pallets to be advanced along the return guideway, substantially as set forth.

3. In an apparatus for treating ore, the combination of a series of independent pallets or ore receptacles, a guide-way along which they travel in one direction during the time the ore is being treated, a return 50 guide-way along which they travel in the opposite direction, means for carrying them from one of the said guideways to the other, and means for delivering to the ore while 55 the pallets are moving along the first mentioned guide way a combustion-supporting gaseous fluid, substantially as set forth.

4. In an apparatus for treating ore, a series of independent pallets or ore receptacles, a device for controlling the movement of a current of air used in treating 60 the ore, means for forming an air-tight clo-

sure for the pallets or receptacles as they travel through the region where the ore is treated, supporting mechanism for the pallets or ore receptacles adapted to permit them to be discharged while supported thereon after they have traveled through the region where the ore is treated, and means for returning them from the delivery end back to the initial end of the region where the ore is treated, substantially as set forth. 75

5. In an apparatus for treating ore, the combination of a series of pallets or ore receptacles, each independent of the others, air forcing mechanism, means for advancing a series of the said pallets or ore receptacles past the air-forcing mechanism, a support or guide-way for the pallets along which they successively move at a relatively high speed after separating from the said series, and means for restoring them from 80 the said guide-way or support to the series passing the said air mechanism, substantially as set forth. 85

6. In an apparatus for treating ore, the combination of a series of independent pallets or ore receptacles, means for supplying ore to them successively, air forcing mechanism, means for advancing a series of said pallets from the ore supplying devices past the air forcing mechanism at a relatively 90 slow speed, means for supporting the pallets or receptacles and adapted to permit them to move toward the ore supplying devices at a relatively high speed, and means for restoring them in position in relation 95 to the ore supplying mechanism, substantially as set forth. 100

7. In a mechanism for treating ores, the combination of a series of independent pallets or ore receptacles, air-moving mechanism, a guideway having a part adjacent to the air-moving mechanism along which the pallets move, and another part at a different level from that of the part first mentioned, and inclined portions uniting the said two parts, and means for elevating the individual pallets from one part of the guideway to the other along one of the inclined portions, the pallets being arranged to travel down the other inclined portion by gravity. 110

8. In an apparatus for continuously treating material, a series of independent disconnected carrying elements, a trackway for supporting the said carrying elements in an end to end series while they are moving 115 through the region where the material is to be treated, means by which the material on the trackway is subjected to moving currents of air as the carrying elements travel along the trackway, means for causing a discharge of the carriers after the material has been treated, and means for returning the said individual carriers to the head of the apparatus. 120

9. In an apparatus for treating material, 130

a series of independent disconnected carrying elements, a guideway along which said carriers travel in an end to end series, means for successively charging the carriers, means for causing air to pass through the material upon the carriers while passing along the said guideway, means for causing the carriers to successively discharge after the material has been treated, and means for 5
10 turning the individual carriers after having discharged to the head of the apparatus.

10. In an apparatus for treating ore, a series of independent disconnected ore carrying elements, movable successively through 15 the region where the ore is treated, means by which the material in the said conveying elements is subjected to moving currents of air while passing the said region of travel, and means for returning the said elements independently one of the other to their initial 20 point of travel for entering the aforesaid region, substantially as set forth.

11. In an apparatus for treating ore, a series of independent disconnected carrying 25 elements, a guideway along which the said elements travel in an end to end series, means for moving the carrying elements in series along the guideway, means for subjecting the material in the carrying elements 30 to moving currents of air while the carrying elements are arranged in series, means for separating the said elements one at a time from the series at the leading end thereof and causing them to discharge their 35 contents, and means for directing the empty carrying elements individually back to the initial end of the said series, substantially as set forth.

12. In an apparatus for treating ore, a series 40 of independent carrying elements, a guideway along which the elements travel in an end to end series, means for moving the carrying elements along said guideway at a relatively slow speed, means for conducting air situated adjacent to the said guideway and arranged to cause the material conveyed by the said carrying elements to be subjected to moving currents of air, means for forming substantially air-tight 45 closures between the individual carrying ele- 50

ments and the said air-conducting means, means for separating the carrying elements from the end of the said series one at a time, and means for causing the return of the individual carrying elements toward the feed 55 end of the said guideway at a speed faster than that at which they travel along the guideway, substantially as set forth.

13. In an apparatus for treating ore, a series of independent disconnected carrying 60 elements, a guideway along which they travel in an end to end series, means arranged to separate the carrying elements from the leading end of the series one at a time, means for directing the individual carrying elements from the discharge end of the apparatus to the feed end thereof, means for allowing the said carrying elements to collect at the feed end of the apparatus before being delivered to the series movable 70 along the said guideway, and means for causing moving currents of air to pass through the material being carried, substantially as set forth.

14. In an apparatus for treating ore, a series of independent disconnected carrying 75 elements each having side walls the edges and the ends of which are smooth, and having also a perforated support for material located between the side walls, a guideway 80 along which the said carrying elements travel in an end to end series, with the ends of the side walls of contiguous elements in close engagement, the guideway being smooth and the edges of the side walls of the 85 carrying elements moving in engagement therewith, thus forming close joints, returning means for directing the carrying elements from the discharge to the feed end of the said guideway, and means for causing 90 moving currents of air to pass through the material carried by the said carrying elements while moving along the said guideway, substantially as set forth.

In testimony whereof I affix my signature, 95 in presence of two witnesses.

ARTHUR S. DWIGHT.
